Attorney, Agent, or Firm—Darby&Darby[57] **CLAIM**

The ornamental design for a bagpack system, as shown and described.

DESCRIPTION

FIG. 1 is a perspective view of a bagpack system showing my new design;

FIG. 2 is a right side elevational view thereof; the left side elevational view being a mirror image thereof;

FIG. 3 is a top plan view thereof;

FIG. 4 is a bottom plan view thereof;

FIG. 5 is a front elevational view thereof;

FIG. 6 is a rear elevational view thereof;
FIG. 7 is a top plan view of the bagpack system unfolded; and,

FIG. 8 is a bottom plan view of the bagpack system unfolded.

The broken line showing of straps is for illustrative purpose only and forms no part of the claim.
